J. C. Page Inventor

United States Patent Office.

T. C. PAGE, OF CHICOPEE, MASSACHUSETTS.

Design No. 2,798, dated October 1, 1867.

DESIGN FOR A SEWING MACHINE.

The Schedule referred to in these Letters Patent and making part of the same.

TO ALL WHOM IT MAY CONCERN:

Be it known that I, T. C. PAGE, of Chicopee, in the county of Hampden, and Commonwealth of Massachusetts, have originated and produced a new Design for a Sewing Machine, of which the following is a full, clear, and exact description, reference being had to the accompanying drawings, making a part of this specification, in which—

Figure 1 is a side view of my design.

My invention consists in the peculiar shape or form given to the support for the needle-arm, and to the support of the wheel which moves it.

In the drawings, B represents the table of the machine upon which the work rests, which may be of a circular form. A is a hollow casing through which runs a rod or shaft, communicating motion to the feed, which operates in or through the table B. Resting upon this hollow casing A is the support of the needle-arm F, and the support C' of the wheel, which gives motion to said needle-arm. These two supports, F and C', are the particular feature of my invention, and I combine and arrange them together, with reference to their shape and working parts, in such manner as to closely resemble the numeral 2. The support F of the needle-arm commences at the point I upon the casing A, and extends upon the curved line I e f g h, rising from the point I, first at an inclination towards the end D of the base A, but as it rises gradually receding from the point or end D, and approaching the point h immediately above the table B. The support F terminates in the head G, having the two projections a b, which are elongated laterally, to admit of the proper attachment and working of the needle-bar. At E is a cylindrical projection, for the proper pivoting of the needle-arm to its support, F, and at H is the projection H', which, with a wire inserted in its top, serves as a spool-holder. At the point I' the support C' of the needle-arm wheel commences, and extends in the curved line I' c d to the point i, the curved line k l m extending upward from the point k to the point e', these two curved lines giving the contour of the support C' of the needle-arm wheel, said support C' terminating in the scroll n, which is connected, by casting, to the support F at the point e', thus adding great strength to both supports, C' and F. At C is a cylindrical projection, for the proper attachment and working of the needle-arm wheel.

Having described my invention, what I claim as new, and desire to secure by Letters Patent, is—

The design for a support for the needle-arm and needle-arm wheel of a sewing machine, in the form of the numeral figure 2, as herein shown and described.

T. C. PAGE.
